UNITED STATES PATENT OFFICE.

REUBEN CASSIUS BRUBAKER, OF EATON, OHIO.

AEROPLANE-PROPELLER MOUNTING.

Application filed January 30, 1924, Serial No. 699,449. Renewed September 15, 1924.

To all whom it may concern:

Be it known that I, REUBEN CASSIUS BRUBAKER, a citizen of the United States, residing at Eaton, in the county of Preble and State of Ohio, have invented certain new and useful Improvements in Aeroplane-Propeller Mountings; and I do hereby declare the following to be a full, clear, and exact description of the invention, such as will enable others skilled in the art to which it appertains to make and use the same.

This invention relates to aircraft, and more particularly to propeller mountings for aeroplanes of the tractor type in which a stationary water cooled motor is employed.

Aircraft equipped with machine guns and other armament have long been recognized as a vital factor in modern warfare, and extensive experiments have shown that a machine gun may be most formidably arranged to fire directly through the propeller. This is true especially of single seated combat and fast scouting planes in which the aviator is also the gunner and must therefore spot his target by directional flight. Many devices for synchronizing a gun to fire between the rapidly revolving propeller blades have been produced without satisfactory results and the more practical plan of arranging the gun to fire through a hollow propeller hub or shaft has been proposed and developed to some extent. Such plan however, necessitates a mounting of the propeller on a secondary spindle or shaft rather than on the extended end of the engine shaft as has heretofore been universally the custom, and no practical or satisfactory means for accomplishing this purpose has thus far been evolved because of the resulting insecurity incident to excessive propeller or engine vibration.

The principal object of this invention is to provide simple, secure and dependable means for mounting an aeroplane propeller on the end of a hollow spindle through which the barrel of a machine gun may be extended to command a wide range.

Another object is to provide a durable and efficient mounting of the character referred to which will be readily adaptable to the various types of aircraft now in use, and inexpensive in cost of manufacture.

Further objects will be apparent from the following description. 55

The invention will first be hereinafter more particularly described with reference to the accompanying drawings which are to be taken as a part of this specification and then pointed out in the claims at the end of 60 the description.

In said drawings, Fig. 1 is a fragmentary perspective view of the "nose" of a conventional aeroplane, illustrating the application of my improved propeller mounting 65 thereto and showing the relation of disassembled parts;

Fig. 2 is a front elevation of the aeroplane radiator with the propeller properly mounted in place, the latter being fragmentarily shown and the outer ring-plate broken away for purposes of clearer illustration; and

Fig. 3 is a fragmentary sectional side elevation of the aeroplane nose, taken on the line 3—3 of Fig. 2, the radiator and cover hood being broken away to illustrate the manner of fastening the hollow spindle in position. 75

Referring to the drawings in which like reference numerals are used to designate corresponding parts throughout the several views, 4 denotes an aeroplane radiator through which one end of the main shaft 5 of the engine is extended, an accommodative opening for such purpose being provided in the lower part of the radiator. A second and larger opening is also provided in the radiator above the lower opening therein and on a vertical plane therewith 80 through which a hollow spindle 6 is extended, the latter being radially flanged at its inner end and rigidly secured to the longeron or anchor plate 7 of the aeroplane by means of bolts passing through holes in 85 said plate (as clearly illustrated in Fig. 3) or in any other desired manner.

An elongated or oblong plate 8 is secured against the front of the radiator by means 90 of apertured lugs extended marginally therefrom, through which holding bolts are passed preferably from the aeroplane frame, said plate being formed with annular openings corresponding with the openings in the 95 radiator through which the ends of shaft 5

and spindle 6 are respectively extended. The plate 8 is also provided at its upper end with an arcuate or substantially semi-circular flange 9 extending forwardly at substantially right angles therefrom.

An open ended cover plate 10, corresponding substantially in contour with the plate 8 and provided with a side portion or marginal flange the extremities of which are 10 adapted to fitting contact with the ends of flange 9, is securable to the plate 8 by any convenient means to form a housing for the assembled parts of the device. The edge of 15 said cover plate at its upper end is arcuately or semi-circularly recessed in opposition to the arcuate flange 9 to provide cooperatively therewith a circular opening through the assembled housing, the axis of 20 said opening corresponding with the axis of the spindle 6.

An annular ring member or hub 11 which is peripherally toothed or provided with a gear portion 12 on its inward edge and with diametrically opposed blade retaining lugs 25 13 extending radially therefrom, is applied over the spindle 6 with its gear portion 12 toward the radiator. An annular ball or roller bearing 13, (preferably comprising separable ball or roller retaining rings arranged 30 in opposition to each other, as shown) is interposed between the inner bearing surface of the ring member 11 and the spindle 6, the extended end of the latter being peripherally grooved to receive the 35 bearing and hold the same in place during removal or replacement of the former, thus providing an anti-friction bearing for the propeller hub.

Blades 15 of the propeller are bolted in 40 place upon the respective lugs 13 of the hub member 11, said lugs being formed with inwardly turned flanges adapted to overlap the looms of the blades on their trailing edges. Clamp plates 13a having similarly formed 45 flanges overlapping the looms of the blades on their leading edges are provided in opposition to said lugs, through which the holding bolts are passed to firmly secure the blades to the hub and prevent splitting or 50 dislodgement thereof by centrifugal force.

A gear 16 in mesh with the gear portion 12 of the hub member 11 is securely keyed to the extended end of shaft 5, by which said member together with its attached blades 55 is revolved at the high rate of speed necessary to attain flight.

A fastening ring plate 17 is finally secured in place over the ring member 11 by means of bolts extended into or through the 60 spindle 6, suitable bolt holes corresponding with holes in the plate 17, being provided in the annular edge thereof for such purpose, thus providing a means for securely holding the revolving propeller in place.

It will be readily understood that a ma-

chine gun may be conveniently mounted with its barrel extended through the hollow propeller spindle and moved upon its swivel as desired to command a wide range, and that the dangers attendant upon firing 70 the same through the propeller are wholly eliminated.

Inasmuch as the application, arrangement and operation of the device will be obvious from the foregoing specification it is thought 75 that further explanation or description of the same would be superfluous. It is also believed that the value and dependability of my improved propeller mounting will be readily apparent and further remarks are 80 therefore considered unnecessary.

Since various changes may be made in the details and arrangement of parts without departing from the spirit and scope of my invention, I do not desire to be limited by the 85 appended claims to the specific structure hereinbefore illustrated and described.

Having thus described my invention, what I claim as new and desire to secure by Letters Patent of the United States, is:

1. An aeroplane propeller mounting comprising in combination, an oblong plate secured to the radiator of the aeroplane, said plate having an opening through which the engine main shaft extends, a gear mounted 90 on the extended end of said shaft, a hollow spindle projecting through another opening in said plate, a blade-carrying hub member mounted on said spindle having a peripheral gear portion adapted to meshing engagement with said gear, an anti-friction bearing interposed between the spindle and the hub and an outer ring plate secured to the end of the spindle against the hub member, to hold the latter in place. 95

2. An aeroplane propeller mounting comprising in combination, an oblong plate secured to the radiator of the aeroplane, said plate having an opening through which one end of the engine shaft extends, a driven gear secured on the extended end of said shaft, a hollow spindle projecting through another opening in said plate, a blade-carrying hub member revolvably mounted on 110 said spindle, having a continuous peripheral gear portion adapted to intermeshing engagement with said shaft driven gear, an antifriction bearing interposed between said hollow spindle and said hub member, and an outer ring plate secured to the extended 115 end of the spindle against the hub member to prevent displacement of the latter. 120

3. An aeroplane propeller mounting comprising in combination, an oblong plate secured to the radiator of the aeroplane, said 125 plate having an opening through which the engine shaft extends, a gear mounted on the extended end of said shaft, a hollow spindle projecting through another opening in said plate, a revolvable blade-carrying hub mem- 130

- ber mounted on said spindle having a peripheral gear portion in intermeshing engagement with said gear, an anti-friction bearing interposed between the spindle and 5 the hub member, an outer ring plate bolted to the end of the spindle against the hub member to securely hold the latter in place and a cover plate secured to said oblong plate to provide a housing for the several 10 parts.
4. An aeroplane propeller mounting comprising in combination, an oblong plate secured to the radiator of the aeroplane, said plate having an opening through which one 15 end of the engine shaft extends, a driven gear secured on the extended end of said shaft, a hollow spindle projecting through another opening in said plate, a blade-carrying hub member revolubly mounted on said 20 spindle having a continuous peripheral gear portion in intermeshing engagement with said driven gear, an anti-friction bearing interposed between the hollow spindle and the hub member, an outer ring plate bolted 25 to the end of said spindle against said hub member to securely hold the latter in place, and a cover plate secured to said oblong plate to provide a housing for the several parts.
5. An aeroplane propeller mounting comprising in combination, an oblong plate having apertured marginal lugs by which it is secured against the radiator of the aeroplane, and an opening through which one 30 end of the engine shaft extends, a driven gear secured on the extended end of said shaft, a hollow spindle secured to the aero- 35 plane frame and projecting through another opening in said plate, a propeller blade-carrying hub member revolubly mounted 40 on said spindle having a continuous peripheral gear portion in intermeshing engagement with said driven gear, an anti-friction bearing interposed between the hollow spindle and the hub member, an outer 45 ring plate bolted to the end of said spindle against said hub member to securely hold the latter in place, and a cover plate secured over said oblong plate to provide a closed housing for the several parts.
6. An aeroplane propeller mounting comprising in combination, an oblong plate secured to the radiator of the aeroplane, said plate having an opening through which the engine shaft extends, a gear mounted on the extended end of said shaft, a hollow spindle projecting through another opening in said plate, a blade-carrying hub member mounted on said spindle having a peripheral gear portion in intermeshing engagement with said gear, and an outer ring plate secured to the end of the spindle 55 against the hub member to hold the latter in place.
- In testimony whereof I affix my signature 60 in the presence of two witnesses.
